(57) **CLAIM**

The ornamental design for a cracking die for a nutcracking die assembly, as shown and described.

DESCRIPTION

FIG. 1 is a perspective view of a cracking die for a nutcracking die assembly which embodies the present invention;;

FIG. 2 is a side elevation view of the cracking die shown in FIG. 1;

FIG. 3 is a front elevation view of the cracking die shown in FIG. 1;

FIG. 4 is a rear elevation view of the cracking die shown in FIG. 1;

FIG. 5 is a sectional view taken along the line 5—5 in FIG. 3;

FIG. 6 is a perspective view of a second embodiment of a cracking die for a nutcracking die assembly which embodies the present invention;

FIG. 7 is a side elevation view of the cracking die shown in FIG. 6;

FIG. 8 is a front elevation view of the cracking die shown in FIG. 6;

FIG. 9 is a rear elevation view of the cracking die shown in FIG. 6; and,

FIG. 10 is a sectional view taken along the line 10—10 in FIG. 8.
